UNITED STATES PATENT OFFICE.

LON KIMBALL, OF FORT SMITH, ARKANSAS.

MOLD-JACKET.

1,002,522.

Specification of Letters Patent.

Patented Sept. 5, 1911.

Application filed May 6, 1911. Serial No. 625,605.

To all whom it may concern:

Be it known that I, LON KIMBALL, a citizen of the United States, residing at Fort Smith, in the county of Sebastian and 5 State of Arkansas, have invented certain new and useful Improvements in Mold-Jackets, of which the following is a specification.

This invention relates to mold jackets or 10 binders and weights used in metal founding for the purpose of holding the mold together and protecting the same during the casting operation, and after the removal of the flask.

15 The object of the invention is to provide an improved device of the kind, which will have advantages in construction and operation as compared to devices heretofore provided for the same or a similar purpose.

20 The device comprises a top plate, side and end plates, and a clamping frame adapted to press and hold the sides of the jacket together; and an important advantage of the construction is that the top plate 25 and sides are loosely connected and will accommodate themselves to slight variations in molds, incident to variations in size of flasks.

A further novelty of construction is that 30 the various parts are separable, so that clogging is prevented, and bursting of the mold will not destroy the effectiveness of the jacket for further use.

Various other advantages will be apparent to those skilled in the art, from the 35 structure as disclosed in the following specification and the accompanying drawings.

In the drawings,—Figure 1 is a perspective view of the jacket, in closed position. Fig. 2 is a perspective view illustrating the application of the jacket to a mold, as the jacket is about to be put in position and before it is tightened on the mold. Fig. 3 is 40 a plan view of the top plate. Fig. 4 is a perspective view of one of the end plates. Fig. 5 is a detail in section of the clamping frame.

Referring specifically to the drawings, 45 indicates a top plate which is made with openings 7 for gating the casting in the mold and for allowing the escape of gases from the mold, as well as to lighten the structure. This plate is provided at its 50 edges with extending eyes or loops 8, which serve the purpose of connecting the sides

and ends to the top plate as hereinafter described.

The side plates are indicated at 9 and end plates at 10. These plates are preferably cast with openings 11 therein to lighten the jacket and allow the escape of gases. Each side and end plate is provided at its upper edge with hooks 12 which are adapted to fit into or through the eyes 8, 60 the points of the hooks being directed outwardly. The eyes are somewhat larger than the bodies of the hooks, so that the latter will have a certain amount of play in the eyes, in order that the walls of the 65 jacket may accommodate themselves to slight variations in the size of the molds. When the parts are assembled the side and end plates are supported by or hang from the eyes at the edge of the top plate, in a 70 loose manner, and the shape of the hooks 12 is preferably such that the plates will tend to swing or open outwardly to a certain extent, in consequence of the point of suspension being slightly offset from the plane of 75 the plates, when the hooks are resting on the eyes. Each of the side and end plates is made or provided with external inclined or wedge shaped ribs 13, extending vertically, and conveniently positioned directly 80 under or forming a continuation of the hooks referred to, although this particular arrangement is not essential.

A clamp or binding frame 14 extends 85 around the wall of the jacket, and this is of 90 such proper size that its inner edge rests against the ribs 13, and when pushed down the wedging action of the ribs presses the plates together, and against the sides of the mold on which the jacket is placed. When 95 the binder frame is lifted it contacts with the underside of the eyes 8, and thereby supports the jacket when it is being placed on or removed from the mold, as shown in Fig. 2, in which position, as above stated, 100 the plates will tend to swing apart slightly so that the jacket may be readily placed upon or drawn from the mold. The binder frame 14 is thus confined between the extended eyes on the top plate and the lower 105 part of the inclined ribs, and hence after the parts are once assembled they are all held together without possibility of accidental separation.

In order that the binder frame may be put 110 in place, it is necessary that some of the ribs 13 be detachable, and I have so illustrated

the same in Fig. 4, on one of the end plates, the ribs being fastened to the plate by any suitable means, such as screws 15. These screws may be taken out and the ribs taken off to permit the binder frame to be slipped on or off as necessary. After the binder frame is taken off, the side plates can be detached from the top plate by swinging the former outwardly to drop the hooks from 10 the eyes, but while the binder frame is in position it is impossible to detach the parts.

In the use of the device, the flask having been removed from the mold, the jacket is lifted by means of the binder frame, permitting the walls to open or swing outwardly and the jacket is then lowered on or around the mold. The frame 14 is then pressed down, and by contact with the wedge ribs 13 closes the sides and end and presses 20 them inwardly against the mold, thereby clamping and holding the same during the casting operation. The top plate acts as a weight, as usual.

Various modifications may be made in the 25 structure, within the scope of the invention. Although shown as rectangular, it may be round, triangular, or in any other shape to correspond to the mold or flask.

Having thus described my invention, what 30 I claim as new, and desire to secure by Letters Patent is:—

1. A mold jacket comprising a top plate having eyes at the edge thereof, adjustable sides having hooked projections engaging in 35 said eyes, and a frame extending around the

sides and adjustable to clamp the sides against the mold.

2. A mold jacket comprising a top plate having projecting eyes at the edge thereof, adjustable sides having hooks at the upper 40 edge thereof loosely engaged in said eyes, and a vertically adjustable clamping frame extending around the sides and confined by said eyes when the frame is lifted.

3. A mold jacket comprising a top plate 45 having eyes at the edge thereof, sides having hooks at the top edges thereof, extending through said eyes, the points of the hooks projecting outwardly and adapted to rest on said eyes, so that the sides will swing open 50 when free, and a clamping band extending around the sides and adapted to close the same.

4. A mold jacket comprising a top plate having openings at the edge thereof, side 55 plates having hooks at the top edge loosely engaged in said openings, whereby the side plates are flexibly hung from the top plate, said side plates having inclined ribs on the outer side thereof, and a binding frame extending around the side plate and adjustable up and down thereon and confined between 60 said ribs and top plate.

In testimony whereof, I affix my signature in presence of two witnesses.

LON KIMBALL.
